UNITED STATES PATENT OFFICE.

JOHN WRIGHT, OF HOOSICK FALLS, NEW YORK.

WHISK-BROOM.

SPECIFICATION forming part of Letters Patent No. 399,308, dated March 12, 1889.

Application filed November 23, 1886. Serial No. 219,667. (No model.)

To all whom it may concern:

Be it known that I, JOHN WRIGHT, a citizen of the United States, residing at Hoosick Falls, in the county of Rensselaer, State of New York, have invented certain new and useful Improvements in Whisk - Brooms, of which the following is a specification, reference being had therein to the accompanying drawings.

10 This invention has relation to improvements in whisk-brooms, and my object is to provide a shield or socket and handle for the same, whereby extra fastenings or cording for the straws thereof are rendered unnecessary, and 15 a finished appearance is given to the broom.

The invention consists in certain features of construction hereinafter specified, and particularly pointed out in the claims.

Referring to the drawings, Figure 1 is a 20 side elevation of a whisk-broom provided with my improvements. Fig. 2 is a like view, the shield and handle being shown in central vertical section. Fig. 3 is a perspective of the handle-cover and socket formed in one piece and detached from the broom. Fig. 4 is a 25 side elevation of a broom provided with the integral handle-cover and socket shown in Fig. 3.

Like letters of reference indicate like parts 30 in all the figures of the drawings.

A represents an ordinary whisk-broom, which, as usual, is secured to an inner core or handle, A', by means of coils of wire A². Adapted to fit snugly upon the upper portion 35 of the broom is a shield or socket, B, which may be formed either of sheet metal, pulp, leather, paper, celluloid, or other desirable material. This shield, to facilitate its manufacture, may be either struck up by suitable 40 dies or molded, as the nature of the material used may necessitate. If molded or pressed, it is preferably made in a single piece without seam. If desired, the surface may be ornamented by any fancy design, as shown, 45 which may be formed by the die or mold. The upper portion of the shield is formed with the ferrule B', made integral therewith, and having the shoulder or swell B².

C represents the handle-cover, which, in 50 this instance, is formed as a tube. The shield is first placed upon the broom, after which the handle-cover is placed in position,

the lower end thereof resting upon the shoulder of the ferrule B'. Adapted to fit upon the top of the core A' and bear against the 55 upper end of the handle-cover C is a cap, D, through which and into the core is passed a binding-screw, E, at the outer end of which is a suspension-ring, E'.

The parts now being in position upon the 60 broom, it will be seen that by turning the binding-screw so as to pass deeper into the core A' the cap D will press upon the handle-cover C, which in turn will bear upon the shoulder B² of the shield B, and it (the shield) 65 will bear upon the broom, drawing the several parts and broom snugly into position. The handle may or may not be provided with a cap. In the latter instance the ring is passed directly through the upper end of the 70 handle cover and core, as indicated in Fig. 4. I prefer, however, to make the shield B, ferrule B', and handle-cover C, if molded or pressed, in a single integral piece, and if struck up or stamped out with dies in two 75 halves united along their edges, as shown, each half having the corresponding parts of the shield, ferrule, and handle-cover formed integral thereon.

I am aware that shields have been provided 80 for brooms, and that the halves thereof have been connected to the broom and together by means of bolts or screws passing through the halves and the broom, and I therefore do not broadly claim a shield for a broom as of my 85 invention; but,

Having described my invention, what I claim is—

1. The combination, with a broom, of a 90 shield and handle-cover, and of a suspension device connected with the handle-core, and serving to maintain the shield and handle-cover in position, substantially as specified.

2. The combination of the broom A, having the core A', the shield B, having the swell B², 95 cover C, cap D, and suspension device E', seated in the core, substantially as specified.

In testimony whereof I affix my signature in presence of two witnesses.

JOHN WRIGHT.
